UNITED STATES PATENT OFFICE.

ARTHUR D. BAKER, OF BROOKLYN, NEW YORK.

OPEN-TOED HORSESHOE.

SPECIFICATION forming part of Letters Patent No. 479,111, dated July 19, 1892.

Application filed March 9, 1892. Serial No. 424,320. (No model.)

To all whom it may concern:

Be it known that I, ARTHUR D. BAKER, of Brooklyn, county of Kings, and State of New York, have invented a certain new and useful Improvement in Horseshoes, of which the following is a specification.

This invention relates to shoes for horses; and it consists of the novel construction and arrangement of parts, as hereinafter set forth.

10 In the accompanying drawings, Figure 1 is a face view of a shoe embodying my invention. Fig. 2 is a section on the line 2' 2' of Fig. 1. Fig. 3 is a rear end view. Fig. 4 is a view similar to Fig. 1, but showing the shoe without calks. Fig. 5 is an enlarged detail of a portion of the shoe.

Referring by letter to the drawings, A designates the shoe joined together at the rear ends by means of a transverse portion A'; but 20 at the forward end the shoe is separated one side from the other, as shown at a, so that in effect the shoe comprises two side portions a' a², joined together at the rear end, but free at the forward ends. By this construction 25 the portions a' a² will readily yield laterally or spread slightly apart at the forward end to allow for the expansion or contraction of a hoof. The transverse portion A', besides serving to hold the parts a' a² together, may 30 also serve as a protector for the frog of the hoof. With this end in view I shape it to conform substantially to the shape and size of the natural frog. It has a forward projection a³ to extend over the apex of the natural frog, and it is slotted from its rear edge 35 forward, as at a⁴, which will allow a slight

lateral expansion and contraction of the parts a' a² of the shoe at the rear ends. The slit a⁴ also gives free access for air to the natural frog. If desired, each portion a' a² may be 40 provided with a toe-calk b and with a heel-calk b'. The portion A' may also be provided with calks b².

In Fig. 4 I have shown the shoe and frog protector with the calks omitted, which may 45 be desirable for shoes where lightness is a feature to be secured.

In Fig. 5 I have shown a metal frog-protector which may be readily and rigidly attached by welding to any ordinary shoe. It is provided with lateral wings c, which may be 50 welded to the shoe in a manner well understood by a person skilled in the art.

This shoe may be made of any serviceable material.

Having described my invention, what I claim is—

1. A horseshoe consisting of two side portions 60 separate one from the other at the forward ends and joined at the rear ends by a transverse portion rigidly attached to the shoe and providing a frog-protector, substantially as specified.

2. The combination, with the shoe, of the transverse portion joining the rear ends thereof and conforming substantially to the shape of a natural frog and calks on said shoe and transverse portion, substantially as specified.

ARTHUR D. BAKER.
